UNITED STATES PATENT OFFICE

2,425,561

POCKET PEN AND PENCIL PROTECTOR

Frederick W. Quidas, New York, N. Y.

Application December 12, 1945, Serial No. 634,447

1 Claim. (Cl. 24—3)

1

This invention relates to improvements in means for securing small articles, such as pens, pencils, combs, and the like, in a pocket.

The invention is preferably made of elastic, or rubber-like materials in the manner, as will be hereinafter fully described.

With the above and other objects in view, this invention consists of the novel features of construction, combination and arrangement of parts, hereinafter fully described, claimed and illustrated in the accompanying drawing, forming part of this specification, and in which similar characters of reference indicate corresponding parts in all views, and in which:

Figure 1 is a front elevational view, showing my device with several articles arranged therein.

Figure 2 is a vertical transverse sectional view, taken on the line 2—2 of Figure 1.

Figure 3 is a front elevation of my device, with parts broken off, showing a slight modification of the device; while

Figure 4 is a vertical transverse sectional view, taken on the line 4—4 of Figure 3.

Figure 5 is a front elevational view, with parts broken off, showing another modification of my invention.

Figure 6 is a transverse view on the line 6—6 of Figure 5.

Figure 7 is a front elevational view, with parts broken off, showing a further modification of my invention.

Figure 8 shows a transverse sectional view, taken on the line 8—8 of Figure 7.

Figure 9 is a front elevational view, with parts broken off, showing a still further modification of my invention; while

Figure 10 is a transverse sectional view, taken on the line 10—10 of Figure 9.

Figure 11 is a top plan view of Figure 9.

Referring more particularly to the drawings, the numeral 10 indicates a piece of rubber-like material, having the indentations 11; this piece 10 is preferably of a shape equal to the inner contours of a pocket, so that when inserted in the latter it will be held tightly in place therein, partly due to its rubber characteristic, causing a certain amount of friction, and partly due to a gripping effect brought about by the said indentations 11.

The said piece 10 has stamped out therein sleeve-like portions 12 adapted to receive therein a pencil 13, a pen 14 and a comb 15, said articles are held in place by portions 16 also stamped out in said piece 10, and pressing said articles up against the inner walls of the sleeves 12.

The piece 10 may also be formed with small projections 17 at the bottom, upon which said articles may rest.

The modifications shown in Figures 3 and 4 are to the effect that the indentations 11 in Figure 1 are omitted herein, while the piece 10 at its upper end is provided with elongated extensions

2

18 adapted to spread out in a pocket and retain the piece 10 rather securely therein.

In Figures 5 and 6 the modifications are to the effect that the sleeve-like portions are formed with slits therein; the upper slits 12' being of an even vertical cut, while the lower slits 12'' have the form of a V-shape. In this construction the portions 16 in Figure 1 are omitted.

In Figures 7 and 8 the construction of the 10 sleeve-like members 20 is to the effect that the lower portions 21 thereof are bent inwardly with a vertical cut 22 in the center thereof, in order to produce a gripping effect upon the articles inserted in said sleeve-like members.

15 In the Figures 9, 10 and 11 is shown the base 10, to which is secured in any convenient manner, such as by gluing, a set of somewhat semi-circular sleeves 24, formed with inward projections 25.

20 It will be apparent that one of the great advantages of this device is that no metal is used therein; thus the usual metal clip that gradually wears down and tears the edge of a pocket is entirely absent in this invention; the latter is nevertheless held in the pocket with even greater security than when a clip is used, inasmuch as the device, when inserted in a pocket, with the flaps, as shown at 18 in Figure 3, or the saw-tooth edges, as shown at 11 in Figure 1, very 25 slightly bent or curved, will, when said elongated extensions or edges spread out after entering the pocket, be fitting closely to the extreme contours of the inside of the pocket.

It is obvious that changes may be made in the 30 form, construction and arrangement of the several parts, as shown, without departing from the spirit of the invention, and within the scope of the appended claim, and I do not, therefore, wish to limit myself to the exact construction and arrangement shown and described herein.

40 What I claim as new and desire to secure by Letters Patent of the United States is:

A device, as described, comprising a flexible member, sleeves arranged upon the latter, projecting portions integral with said flexible member and cooperating with said sleeves, supporting means below the latter, and means formed upon said flexible member whereby to engage the inside of a pocket, said means consisting in saw-tooth edges formed upon each side of the flexible member.

FREDERICK W. QUIDAS.
